OF SWEDEN

TELEPHONE PLANT

Application filed May 26, 1931, Serial No. 540,158, and in Sweden May 31, 1930.

The present invention refers to such automatic and semi-automatic telephone systems which are provided with registers and in which the subscribers' lines are connected to the registers over call finders and appertaining cord lines in such a manner that each call causes the starting of a plurality of call finders, the connection being established over that call finder which first finds the calling subscriber's line. More particularly the invention refers to such systems of the latter kind in which each register, by means of the cord finder appertaining to the register, first selects a call finder which is free for the time being whereupon only the call finder thus selected is started for the purpose of hunting for the calling subscriber's line. Systems of this kind are known in which the starting circuits of the call finders as well as the impulse circuits of the register are adapted to be connected to the call finders or the cord lines respectively by means of the cord finder appertaining to the register. As distinguished from the latter system the present invention is characterized in that the starting circuits of the call finder and the impulse circuits of the registers are adapted to be selectively connected to the call finders or cord lines respectively by means of separate switching devices. Through such a distribution of the starting circuits and the impulse circuits to mutually independent switching members a greater latitude is gained in regard to the manner of arranging the switching circuits, which in turn renders possible the simplification and reduction of cost of the apparatus equipment required for starting the call finders and connecting the registers into circuit. The fact that the starting of the call finders takes place before the register is made operative may, by way of example, be made use of according to the invention in such a manner that the requirement for a special cord finder for connecting-in the starting circuits is eliminated; in that, for instance, an auxiliary apparatus appertaining to the register may be arranged to hunt for and start an idle call finder by means of a preparatory switching operation, said auxiliary apparatus being

made operative first after the register has been connected to the cord line for the purpose of carrying out certain regulating functions. At the same time the switching members required for the switching-in of the impulse circuits of the register may be simplified as they are not called upon to carry out any selector function and may thus, by way of example, consist of relays appertaining to the different cord lines.

The invention will be more closely described with reference to the accompanying drawings. Figure 1 is a diagrammatic representation intended to illustrate the principle of the invention, whereas Figure 2 shows a circuit diagram of an arrangement according to the invention.

Figure 1 illustrates diagrammatically a plurality of cord lines SL with appertaining call finders AS and group selectors GV. All cord lines are assumed to be accessible to one and the same group of subscribers, to which group also a number of registers RE belong. If the group of subscribers comprises, by way of example, 500 subscriber's lines said group may be served by 8 registers. In the shown example said registers are distributed over the different cord lines SL in such a manner that each register may connect itself only to some of the cord lines appertaining to the subscriber's group. Said cord lines are thus divided into a plurality of groups G, in the present case 8 groups each of which is allotted to an appertaining register. Each register is adapted to connect itself to an arbitrary one of the cord lines SL in the appertaining group G by means of a switching device KS. Said switching device may be of arbitrary kind, for instance a cord line searcher. It may also consist of relays. On the drawing the small circles in the junction points between the different lines indicate the connections which may be established by means of the different switching apparatuses. The lines RL represent those impulse circuits over which the registers are set and over which the setting of the selectors is controlled.

The figure also illustrates the arrangement of the starting circuits of the call finders. Each call finder AS is provided with a start-

ing relay SR included in the appertaining starting circuit. The selection and starting of a free call finder is according to the invention effected by means of the switching apparatus KS which is independent of the switching apparatus SS and which may be of arbitrary kind, for instance a selector adapted to be electromagnetically set. The connections which may be established by said switching apparatus are indicated by means of circles in the junction points between the different lines. The starting circuits also include contacts SK which are opened as soon as the call finder is energized and, further, contacts RK which are disposed in the circuit branches appertaining to the different registers and which are open when the appertaining register is used and, finally, a contact TK adapted to be closed by a relay STR as soon as a call occurs, said relay being common to the whole group of subscribers. If upon a call the switching apparatuses SS are set on call finders AS which are idle for the time being the starting circuits will be closed by means of the starting relays SR appertaining to said call finders over contacts RK of free registers. In case the call finder should be engaged the switching apparatus SS will immediately hunt for a free call finder and start the same. As long as a register is engaged none of the appertaining call finders can be started. It is thus evident that each call causes the starting of only one call finder for each free register. As soon as a call finder is started the switching apparatus KS may be actuated for the purpose of connecting the setting and control circuits of the register to the corresponding cord line. Said connection into circuit does not necessarily include a selective switching operation for the reason that the cord line has already been selected by the switching apparatus SS. For the connecting-in of the setting and control circuits of the register simple relays may therefore advantageously be used.

Figure 2 shows a simplified circuit diagram for a portion of a talking connection in an automatic telephone plant comprising a call finder AS, a group selector GV, and a register RE. The selectors are machine driven and of the kind, the contact arms Ka, Kb, Kc of which have two setting movements in the same plane namely a turning movement for selecting a line group and a radial movement for selecting a certain line. A fourth contact arm Kd has only a turning movement. The motion mechanism is controlled in known manner by means of two switching magnets CVS and CRS of which the former brings about a turning motion and the latter a radial motion.

The parts appertaining to the register RE are enclosed within the dot and dash rectangle. The register is provided with four impulse receivers R₁, R₂, R₃, R₄ adapted to be

set stepwise by means of the current impulses sent out from the subscriber. The register is also provided with an electromagnetically controlled auxiliary apparatus SS adapted to hunt for a free call finder and also to bring about the successive connecting into circuit of the driving magnets RM₁, RM₂, RM₃, RM₄ of the impulse receivers R₁, R₂, R₃, R₄ to the impulse circuit controlled by the subscriber. For this purpose the auxiliary apparatus SS is provided with three contact arms A₁, A₂, A₃ disposed on the same shaft B, of which contact arms the first one, A₁, controls the starting circuits of the call finders whereas the second, A₂, controls the circuits for the switching magnet SM of the auxiliary apparatus, and the third A₃ the circuits for the driving magnets RM₁, RM₂, RM₃, RM₄. The contact arms are adapted to be set in 10 positions, of which the first one is the normal position. The driving mechanism consists of a toothed wheel C disposed on the shaft B, a spring actuated stepping pawl D engaging said toothed wheel, and a spring E which tends to turn the toothed wheel in the direction indicated by the arrow P, a stepwise motion being imparted to the wheel in known manner under control of the electromagnet SM in such a way, that the contact arms are brought forward a half-step when the magnet SM attracts its armature F and a further half-step when the magnet SM drops its armature.

The five first contact positions of the auxiliary apparatus SS are intended for the selection of a free call finder whereas the following four contact positions are intended for the connecting-in of the different impulse receivers R₁, R₂, R₃, R₄. A plurality of relays RR₁, RR₂, RR₃ serve to control the auxiliary apparatus for the purpose of hunting for a free call finder, whereas the continued motion of the auxiliary apparatus occurs under the control of an impulse relay RR₄ and two slow-acting relays RR₅ and RR₆.

The connection of the setting and control circuits of the register to the call line SL is in the shown example effected by means of a relay RN₁ appertaining to the cord line.

The arrangement operates in the following manner.

Upon a call from a subscriber AB a circuit 1 is closed over the subscriber's line L through a line relay LR which attracts its armature and connects test potential to the third wire of the subscriber's line over the contact 2. The line relay also closes at its contact 3 a circuit 4 for a relay LGR which is common to the subscriber's lines connected to the same contact row in the call finder AS. The call finders are in this case assumed to have a capacity of 500 lines, the contacts a, b, c of which are disposed in 25 rows with 20 contact groups in each row. Simultaneously herewith the test contact d appertain-

ing to the same contact row obtains test potential over the contact 3. The relay LGR in turn closes the circuit 5 for a starting relay STR which is common to all the subscriber's lines in the 500-group in question. When the latter relay attracts its armature the starting circuit 6 is closed for one of the call finders belonging to each free register. It may initially be assumed that the first of the call finders appertaining to the register RE is free for the time being. The circuit 6 is then closed directly over the contact arm A₁ in its normal position. In said circuit the relay RR₁ is included which at its contact 7 cuts out the relay RR₃ which is slower than RR₁ in attracting its armature and therefore on this occasion remains inoperative. The circuit 6 extends over a contact 8 of the call finder, which contact is open when the call finder starts its radial motion, and over a contact 9 of the group selector which is opened when the group selector leaves its normal position. It also includes the starting relay SR of the call finder which relay 25 now attracts its armature and causes the starting of the call finder.

In case the first call finder should be engaged the circuit 6 is not immediately established, but a circuit through the relay RR₃ over the contact 7 and the common part of the circuit 6 is at first closed. The relay RR₃ is energized, thereby connecting the starting circuits for all call finders appertaining to the register in question to the operative winding of the relay RR₂. The latter will consequently be energized, provided any one of the said call finders is free, the relay RR₃ being then immediately again disconnected at the contact 10. The relay RR₂ simultaneously connects itself into a holding circuit over its contact 11. When the relay RR₂ attracts its armature a circuit 12 is closed through the control magnet SM, the contact arms of the auxiliary apparatus being then brought forward half a step. The contact arm A₁ then makes contact with the contact k₁₂ which is connected to the starting circuit of the other call finder. The circuit 12 is, however, simultaneously interrupted, as the contact arm A₂ now occupies an intermediate position between the contacts k₂₁, k₂₂. In consequence hereof the contact arms are brought forward another half-step, the arm A₁ then still making contact with the contact k₁₂ whereas the arm A₂ now makes contact with the contact k₂₂. In case also the other call finder is engaged the control magnet SM now receives a current impulse over the contact k₂₂, whereby the contact arms are brought forward a further half-step, so that the arm A₁ makes contact with a contact k₁₃ connected to the starting circuit of the third call finder. In case the latter call finder is free also the said circuit 6 is immediately closed; the relay RR₁ being

then energized opening the contact 13 in the circuit 12 which thus now remains interrupted. Consequently the contact arms remain in their third position. Simultaneously herewith the relay RR₂ is disconnected. In case all of the call finders appertaining to the register should be engaged the relay RR₂ does not receive any current, wherefore the contact arms in this case remain standing in the normal position until any one of the call finders becomes free the auxiliary apparatus SS being then started in the above described manner completing the starting circuit 6.

When the starting relay SR attracts its armature a circuit 14 through the switching magnet CVS is closed, the call finder being then started and carrying out its turning motion. In reality a plurality of call finders within the subscriber's group in question have been started simultaneously, as will be seen from Figure 1. The call finder which first finds the contact row to which the calling subscriber is connected will then be set for radial motion while the other call finders stop, or in case several calls occur continue their turning motion. When the contact arm K_d makes contact with the test contact d for the contact row in question a circuit 15 is closed through a test relay RS₁ which attracts its armature and interrupts the circuit 14, the turning motion of the call finder then stopping. Simultaneously herewith the starting relay SR is short-circuited at the contact 16 of the relay RS₁, the relay SR then dropping its armature and closing a circuit 17 through the switching magnet CRS whereby the call finder is started in a radial direction.

When the relay RS₁ attracted its armature it short-circuited at its contact 18 a counter-acting part of its winding, so that the effective number of ampere-turns of the relay was increased whereby is guaranteed that the relay does not drop its armature on account of the shunting of the relay at the test contact d which occurs when other call finders pass the contact row in question. At the same time the contact row is hereby marked as engaged for other call finders while the first mentioned call finder moves in a radial direction for the purpose of hunting for the calling subscriber's line.

When the call finder finds the calling subscriber's line a circuit 19 is closed over the third wire including the cut-off relay BR of the subscriber and a test relay RS₂. The relay BR cuts off the line relay LR which drops its armature and interrupts the circuit 4, the test potential of the contact d disappearing simultaneously herewith. The contact 2 of the relay IR is, however, maintained closed through the action of the relay BR. The relay RS₂ interrupts the circuit 17, the call finder then stopping on the contacts of the calling subscriber's line. The relay RS₂ also

short-circuits at its contact 20 the relay RS_1 which thus drops its armature. The circuit 19 is then kept closed over a contact 21 of the relay RS_2 whereby at the same time a part 19 of the relay winding is disconnected. The relay RS_2 also closes a circuit 22 through the connecting relay RN_1 of the register which relay then attracts its armature and in turn closes a circuit 23 extending over the subscriber's line and including the impulse relay RR_4 which now attracts its armature. Then a circuit 24 is closed for a slow-acting relay RR_5 which in turn closes a circuit 25 for the relay ER which attracts its armature and opens two contacts 26, 27 in the circuit 6. Said latter relay also closes at its contact 28 a circuit 29 for the control magnet SM extending over the contact arm A_2 . In consequence hereof the auxiliary apparatus SS is brought forward stepwise in the previously described manner until it reaches the sixth position in which it remains standing with the contact arm A_3 on the contact k_{36} . Meanwhile the subscriber has in known manner received a buzzer signal which indicates that the impulse sending may start. During the impulse sending the relay RR_5 maintains its armature attracted. When the impulse relay RR_4 for the first time drops its armature the circuit 30 is closed for the slow-acting relay RR_6 which then attracts its armature and closes the circuit 31 for the control magnet SM , the auxiliary apparatus being then brought forward one half step. Also in the new position, however, the arm A_3 remains in contact with the contact k_{36} . Each time the impulse relay RR_4 drops its armature a current impulse is sent over the circuit 32 through the driving magnet RM_1 for the impulse receiver R_1 which thereby is set in accordance with the first digit in the desired subscriber's number. At the end of the first impulse series the impulse relay RR_4 remains current carrying and in consequence hereof the relay RR_6 drops its armature. Then the circuit 31 is interrupted and the contact arms of the auxiliary apparatus are brought forward a further half-step to the position 7 in which the contact arm A_3 makes contact with the contact k_{37} . The subsequent impulse series will consequently set the impulse receiver R_2 . At the end of the second impulse series the contact arm A_3 , which at the beginning of said impulse series was brought forward a further half-step while maintaining contact with the contact k_{37} , will be brought forward to the position 8 in which the impulse receiver R_3 is connected into circuit, which impulse receiver thereafter is set by means of the third impulse series. The connecting into circuit and setting of the fourth impulse receiver R_4 is effected in a similar manner while the contact arm A_3 remains in the ninth position. When the relay RR_6 drops its armature after the sending of

the last impulse series the contact arms of the auxiliary apparatus are brought forward a further half-step whereby the auxiliary apparatus reaches the tenth setting position. Hereafter the setting of group selectors and line selectors is effected in a manner known per se under control of the register. After completed setting of all the selectors included in the talking connection a circuit 33 is closed through a relay RN_2 which attracts its armature and disconnects the connecting relay RM_1 whereby the register is released. At the same time the relay RN_2 connects itself over its contact 34 into the circuit 22 in place of the relay RN_1 . When finally the impulse relay RR_4 is deenergized the slow-acting relay RR_6 receives a current impulse which is interrupted when the relay RR_5 drops its armature. In consequence hereof also the control magnet SM receives a further impulse whereby the auxiliary apparatus SS is brought forward to the starting position. When the relay RR_5 drops its armature also the relay ER is deenergized. The register is now ready for receiving a new call.

We claim:—

1. In a telephone system, a group of subscribers' lines, a number of call finders and cord lines allotted thereto, a number of registers connectible to the said subscribers' lines over the said cord lines and call finders, means to start upon a call a number of call finders corresponding to the number of registers free for the time being, and switching members separate from the said starting means to connect the impulse circuits of the registers to the cord lines.
2. A telephone system as claimed in claim 1 in which the cord lines allotted to the group of subscribers' lines are divided into a number of cord line groups, the registers appertaining to the subscriber's group being allotted to different groups of cord lines.
3. In a telephone system, a group of subscribers' lines, a number of call finders and cord lines allotted thereto, a number of registers connectible to the said subscribers' lines over the said cord lines and call finders, means to start upon a call, a number of call finders corresponding to the number of registers free for the time being, and a number of relays separated from said starting means to connect the impulse circuits of the registers to the cord lines.
4. In a telephone system, a group of subscribers' lines, a number of call finders and cord lines allotted thereto, a number of registers connectible to the said subscribers' lines over the said cord lines and call finders, a control switch allotted to each register, which control switch is adapted upon a call to hunt for and start a free call finder, and switching members separate from the said control switch to connect the impulse circuits of the registers to the cord lines.

5. In a telephone system, a group of subscribers' lines, a number of call finders and cord lines allotted thereto, a number of registers connectible to the said subscribers' lines over the said cord lines and call finders, a switch allotted to each register, which control switch is adapted upon a call to hunt for and start a free call finder, a testing arrangement to prevent the starting of the said control switches when all finders appertaining to the register are engaged and switching members separate from the said control switch to connect the impulse circuits of the registers to the cord lines.
- 15 In testimony whereof we affix our signatures.

KNUT LARSSON.
